Redding, Greeley, O'Shea & Campbell

UNITED STATES PATENT OFFICE.

BENJAMIN SHAPS, OF NEW YORK, N. Y.

GLOBE HANGER FOR LIGHTING FIXTURES.

Application filed April 18, 1928. Serial No. 270,885.

The present invention relates to supporting devices for globes of lighting fixtures wherein the glass is suspended from a suitable hanger so that it may be removed at 5 times for cleaning. The usual form of hanger has included a bell portion provided with set screws which engage the turned-back flange of the globe, each screw being individually adjusted to engage the flange. 10 When the globe is washed, considerable difficulty is experienced in removing it by reason of the fact that the set screws sometimes become jammed. This is quite a disadvantage, particularly when the globe is suspended at a considerable height.

In accordance with the construction embodied in the present invention, the set screws are dispensed with and a suitable frame provided which receives the globe and 20 holds it in a desired position. This construction eliminates the set screws required in many of the old types of hanger and in addition to the ease of mounting, holds the globe securely in place.

25 The invention further contemplates the provision of a hanger upon which the globe may be mounted in a single operation. The hanger is pivoted to lie, normally, in a tilted position so that the recess of the globe will 30 readily pass over it and, after it is within the globe and the latter lowered, suitable flanges of the hanger engage the globe to cause the hanger to be moved to a horizontal position and support the globe at four points.

35 The invention will be understood more readily in connection with the accompanying drawings, wherein:

Figure 1 is a view in section, taken on line 1—1 of Figure 2, and looking in the 40 direction of the arrows.

Figure 2 is a plan view of the globe, showing the manner in which the hanger engages the interior thereof to secure it in the desired position.

45 Figure 3 is a view in section, taken on line 3—3 of Figure 2, and looking in the direction of the arrows.

Referring to the above drawings, α designates a stem upon which a fixture is to be 50 mounted and within which the electric wire is to be carried. The stem carries a bell housing α' which is slidable thereover and may be secured in a desired position by means of a set screw α'' . Within the bell housing, a yoke b is secured to the lower end 55 of the stem α . This yoke is rigidly secured

to the stem and has outwardly diverging arms b' to the lower extremities of which a globe hanger c is pivoted. Hanger c , pivoted to the arms b' at c' , is formed in the 60 shape of a rectangle preferably with the sides thereof equal. It is formed with a horizontally disposed flange c^2 and at the corners thereof, upwardly extending positioning lugs c^3 are provided. 65

When the hanger has been inserted within the globe and the latter lowered, the flange c^2 engages the inner periphery of the globe adjacent the opening and moves the hanger to the position shown in full lines in Figure 1. In this position the globe is supported at four points as clearly shown in Figure 2 and the positioning lugs c^3 prevent lateral movement of the globe with respect to the hanger. The bell housing is slid down 70 to the position shown in Figure 1 and the hanging of the globe has been effected. It will be seen that the hanging of the globe can be readily effected in a single operation, the globe merely being lifted until it receives the hanger within the body thereof, 75 and then lowered until the inner surface adjacent the opening engages the flange c^2 of the hanger. The latter is then moved from the dot and dash lines of Figure 1 to 80 the horizontal position shown.

In order that the hanger will normally lie in a tilted position such as shown in dot and dash lines in Figure 1, one side thereof is weighted. As will be seen in Figure 2, the 90 positioning lugs on the right-hand side of the hanger are made larger than those on the left-hand side. If desirable they may be made of lead or other heavy substance in order that the hanger may normally lie in 95 a position which is tilted sufficiently. Tilting of the hanger in this manner greatly facilitates the hanging of the globe and enables it to be done in a single operation. The above construction does away with objectionable set screws which frequently become loosened and the hanger construction described affords a means for hanging the 100 globe securely and positively in position.

Although the invention has been described 105 in connection with the accompanying drawings, the scope thereof is not to be limited save as defined in the appended claims.

I claim as my invention:

1. A device for supporting a globe comprising a stem, yoke arms carried by the stem, a globe hanger pivoted to the arms, 110

and means carried by the hanger to support the globe against movement transverse to the arms.

2. A device for supporting a globe comprising a stem, yoke arms carried by the stem, a rectangular shaped hanger pivoted to the arms, and means at the corners of the of the hanger for positioning the globe thereon.

3. A device for supporting a globe comprising a stem, yoke arms carried by the stem, and a weighted globe hanger pivoted to the arms, the hanger normally assuming a tilted position when not supporting a globe.

This specification signed this 17th day of April A. D. 1928.

BENJAMIN SHAPS.
